UNITED STATES PATENT OFFICE.

JOSEPH WHITE, OF PISCATAWAY TOWNSHIP, MIDDLESEX COUNTY, NEW JERSEY.

TICKET-PRINTING MACHINE.

1,019,107.

Specification of Letters Patent.

Patented Mar. 5, 1912.

Application filed January 12, 1911. Serial No. 602,209.

To all whom it may concern:

Be it known that I, JOSEPH WHITE, a citizen of the United States, residing in Piscataway township, Middlesex county, State 5 of New Jersey, (whose post-office address is Bound Brook, New Jersey,) have invented certain new and useful Improvements Relating to Ticket-Printing Machines.

This invention has for its object the printing 10 of dates or other designations upon successively presented tickets. These tickets are preferably made in strip form in a roll with the main portion of the ticket printed upon. It is often desirable to have some 15 designating mark printed upon the tickets at the time they are sold, and the machine herein described is arranged to print this date or designation upon the ticket by as simple a means as possible, and at the same 20 time have this designation register with the matter which has originally been printed upon it.

While various machines have been constructed for the purpose of printing tickets 25 to register with matter previously printed upon them, these machines have been arranged so that when they are operated they feed the tickets through the machine; but the machine herein described is arranged so 30 the source of operating power is derived from the ticket strip, and all that is necessary in operating it is to thread the strip in the machine, and by pulling the same through the machine, the mechanism will 35 register itself, so that the tickets will be printed upon in the proper place as each one passes through the machine.

Referring to the drawings, Figure 1 is an elevation of the machine, and Fig. 2 is a 40 sectional elevation of Fig. 1.

The standards 1 and 2 of the machine are mounted upon a base 3 and upon the same base is a standard 4 in which is placed a roll of tickets 5. These tickets as has been mentioned, have been printed upon with the appropriate printing matter and in addition have been punched with notches or holes by means of which the tickets will be registered to the dating machine in a manner to 45 be hereinafter described. The particular 50

form of these notches or punch holes may be varied widely but in the form of ticket shown they consist of three holes, 6. The printing cylinders or rolls of the machine consist of a lower impression roll 7 and an 55 upper or type roll 8 between which the ticket is passed and receives its printing. At the same time these rolls serve as pressure rolls and when the ticket is pulled through between them they revolve, causing the type 60 form (in a manner to be described) to receive its ink and to place its imprint on the ticket.

In order to secure the printing of date on the ticket in the space reserved for it, 65 the tickets or machine must be adjusted by some device. In the machine illustrated this registration is taken care of as follows: The impression cylinder 7 and type cylinder 8 each has a periphery of about two 70 ticket lengths (for a reason to be hereinafter described—preferably slightly less), and the impression surface is provided with two sets of pins 9 (diametrically opposite) which engage the holes of the tickets as the cylinders are revolved when the tickets are pulled 75 between them. The cylinder 8 has holes 10 provided for the pins for clearance purposes. At the time the ticket holes 6 engage the pin 9 it is desirable that the cylinders be 80 placed out of pressure engagement with each other so that the ticket may engage the pins and so locate itself with relation to the cylinders. The method of causing the disengagement may be varied widely 85 but in the preferable form, as shown, the periphery of the cylinder is cut away where the pins are located in the cylinder. This cut-away as shown consists of a flat 11 upon the surfaces of the cylinder, and when said 90 flat surface comes opposite the type cylinder the pressure is removed from the tickets, but held in proper relation by the pins passing through the pin holes. The pin holes are preferably slightly larger than the pins, 95 and the cylinder is made slightly smaller in circumference than two ticket lengths so that the pins will pass into the holes at about their center, or slightly forward of their center, and when the cylinders are re- 100

moved from pressure contact with the ticket because of the flats 11, the ticket will go forward until the back edge of the holes strikes the pins which will rotate the cylinders forward so that they will again grip the tickets and be revolved until the next pins engage the holes, and the previously described operation will be resumed. Thus each ticket will adjust the machine to its 10 holes as it is presented to the machine.

It can be understood that a machine operated by a paper strip which has been scored so that it can be readily separated into individual tickets, and punched for the purpose 15 of registration, should be made as light running as possible, and for this reason the machine has been devised so that it consists of one pair of rolls which serves the dual purpose of feed rolls for adjusting the machine and for printing rolls for printing upon the ticket; although it is to be understood that two pairs of rolls properly geared together may be used without departing from some of the features of the invention.

25 The machine is provided with a series of ink rollers 12, 13, and 14 which contain the ink supply and as the type passes these rolls they are inked for printing.

It can be seen that when the type surface 30 passes the pressure point and places its impression upon the ticket it must be on a level with the surface of the type cylinder 10, and if it remained on a level with the surface at the place where it passed the ink rolls 35 to receive its ink, the body of the cylinder would also have ink placed upon it. In order to avoid this, the type is caused to raise above the surface of the cylinder, and contact with the ink supply. The manner in 40 which this is accomplished may be varied widely but the preferred form is shown in the drawings. The type forms 33 are placed in the sliding type blocks 15 and 16 which hold the type 33, which are provided each 45 with a set of pins 17 and 18. These pins engage annular grooves 19 and 20 formed in the side frames of the machine. These grooves are so formed that when the type blocks pass the pressure point the type surface 50 face is placed at a level with the cylinder, and when they pass the printing rolls, they are raised above the surface of the cylinder to the level of the rings 22 formed on the type cylinder; said rings serving to revolve 55 the ink rolls and distribute the ink.

The impression cylinder 7 is provided with a pair of slots which contain the impression surfaces for the type, which surfaces consist preferably of soft rubber blocks 60 23 located in these slots. The cylinder 7 is provided with a shaft 24 which is mounted in a pair of bearings 25 held in position by a pair of rods 26 around which are coiled a pair of springs 27 which provide the ten-

sion placed upon the strip between the cylinders. These rods have each a set of adjusting nuts 28 by means of which the cylinder may be properly vertically located and the tension regulated. Mounted on shaft 21 of the type cylinder is a gear 29 and mounted on shaft 24 is a gear 30, said gears serving the purpose of keeping the pins and pin-holes, and type and impression surfaces in proper relation to each other. The machine is also provided with proper guides 31 and 32 by 75 means of which the ticket is located and positioned when passing through the machine.

Claims:

1. In a printing machine arranged to print on a continuous strip having register 80 perforations thereon; the combination of a pair of rolls rotated by the strip passing between them in pressure contact therewith, means whereby said rolls are relieved from contact with the strip for a portion of a 85 revolution, and pins on one of said rolls to engage the perforations to adjust the machine in relation to the strip when the rolls are out of pressure engagement therewith.

2. In a printing machine arranged to 90 print on a continuous strip having register perforations thereon; the combination of a type roll and an impression roll rotated by the strip passing between them in pressure contact therewith, pins on one of said rolls 95 for engaging the perforations in the strip; said rolls so arranged that when the pins engage the perforations the pressure contact on the strip will be relieved and the rolls will be adjusted by the perforations.

3. In a printing machine arranged to print on a continuous strip; the combination of a type roll, an impression roll, a radially movable type body in the type roll, an ink roller, bearers on said type roll, means for moving said type body to cause the type face to contact with the ink roller; said ink roller supported by said bearers in such a manner as to clear the surface of the type roll and to be revolved by said bearers.

4. In a printing machine arranged to print on a continuous strip having register perforations thereon; the combination of a type roll and an impression roll, strip adjusting means on one of said rolls, a type segment and a pressure segment on the type roll; said segments alternately engaging the strip between them and the impression roll; said adjusting means engaging the strip at the register perforations when said strip is 115 out of engagement with the type and impression roll.

5. In a printing machine arranged to print on a continuous strip having register perforations thereon; the combination of a type roll and an impression roll, strip adjusting means on the impression roll, a type segment and a pressure segment on the type

roll; said segments alternately engaging the strip between them and the impression roll; said adjusting means engaging the strip at the register perforations when said strip is 5 out of engagement with the type and impression roll.

In witness whereof, I have hereunto set

my hand in the presence of two subscribing witnesses.

JOSEPH WHITE.
